(57) **CLAIM**

I claim the ornamental design for a stretchable computer carrying sleeve, as shown and described.

DESCRIPTION

FIG. 1 is a front perspective view of a stretchable computer carrying sleeve in its first configuration;

FIG. 2 is a front perspective view of the stretchable computer carrying sleeve of FIG. 1 shown in a partially open state;

FIG. 3 is a front view of the stretchable computer carrying sleeve of FIG. 1;

FIG. 4 is a rear view of the stretchable computer carrying sleeve of FIG. 1;

FIG. 5 is a bottom view of the stretchable computer carrying sleeve of FIG. 1;

FIG. 6 is a top view of the stretchable computer carrying sleeve of FIG. 1;

FIG. 7 is a left end view of the stretchable computer carrying sleeve of FIG. 1;

FIG. 8 is a right end view of the stretchable computer carrying sleeve of FIG. 1;

FIG. 9 is a front perspective view of the stretchable computer carrying sleeve of FIG. 1 shown in its second configuration which is reversed relative to its first configuration;

FIG. 10 is a front perspective view of the reversed stretchable computer carrying sleeve of FIG. 9 shown in a partially open state;

FIG. 11 is a front view of the reversed stretchable computer carrying sleeve of FIG. 9;

FIG. 12 is a rear view of the reversed stretchable computer carrying sleeve of FIG. 9;

FIG. 13 is a bottom view of the reversed stretchable computer carrying sleeve of FIG. 9;

FIG. 14 is a top view of the reversed stretchable computer carrying sleeve of FIG. 9;

FIG. 15 is a right end view of the reversed stretchable computer carrying sleeve of FIG. 9; and,

FIG. 16 is a left end view of the reversed stretchable computer carrying sleeve of FIG. 9.

Any textural treatment of a surface shown in FIGS. 1-16 is intended to extend over the entirety of the respective surface of the stretchable computer carrying sleeve. The broken lines shown in the figures are intended to show stitching. The stitching shown includes a lighter top-stitching on the trim and heavier stitching around the periphery.
